UNITED STATES PATENT OFFICE.

FRANK P. MIES, OF CHICAGO, ILLINOIS, ASSIGNOR TO THE PLURAL SYSTEM VENTILATOR CO.

FAN STRUCTURE.

1,049,508.

Specification of Letters Patent.

Patented Jan. 7, 1913.

Application filed January 10, 1910. Serial No. 537,261.

To all whom it may concern:

Be it known that I, FRANK P. MIES, a citizen of the United States, residing at Chicago, in the county of Cook and State of Illinois, have invented certain new and useful Improvements in Fan Structures, of which the following is a specification.

My invention relates to systems and apparatus for ventilating, heating, and cleaning, and has especial reference to systems of this character wherein fans or the like are employed to produce more or less pressure or attenuation of the air or atmosphere as required for accomplishing the desired results.

15 The object of my invention is to apply and use the apparatus of the character usually employed separately for ventilating, heating, and cleaning in a single system, and by so arranging and adjusting said

20 apparatus as to adapt it to perform all of these effects conveniently and economically.

A further object of my invention is to improve generally and specifically the apparatus required for these purposes and to arrange and associate said devices in co-operative relation, so that they may readily be adapted to perform the several functions for which they are respectively designed, without change of relative location.

30 Other and further objects of my invention will become apparent to persons skilled in the art to which it appertains.

In the drawings, I have illustrated an embodiment of my invention, wherein—

35 Figure 1 is a plan view of the apparatus showing the various devices in operative relation and mounted on a single base; Fig. 2 is an enlarged longitudinal section taken on line 2—2 of Fig. 1; Fig. 3 is a similar view taken on line 3—3 of Fig. 1; Fig. 4 is a cross-sectional view looking toward the top taken on line 4—4 of Fig. 3; Fig. 5 is a longitudinal section taken on line 5—5 of Fig. 1; Fig. 6 is a sectional view taken on line 6—6 of Fig. 5; Fig. 7 is an end view showing a part of the base in section taken on line 7—7 of Fig. 1; Fig. 8 is a fragment of the assembled parts shown in Fig. 15; Figs. 9, 10, and 11, are sectional views taken on line 9—9 of Fig. 15, showing the air intake valve in its various positions; Fig. 12 is an elevation of a hose attachment, shown in dotted lines in Fig. 15; Fig. 13 is an enlarged sectional view taken on line 13—13 of Fig. 15; Fig. 14 is a sectional view taken on

line 14—14 of Fig. 13; and Fig. 15 is a sectional plan view showing a schematic arrangement of the devices to carry my system into effective operation.

In all of the views the same reference characters indicate similar parts.

A fan casing, indicated generally by 25, is composed of a lower part, 26, and an upper arch-shaped part, 27, within which the fan, 28, is rotated and has bearing supports. 65 The intake of the fan is near its axis. The part 26 is provided with two discharge outlets, 29 and 30. Midway between these outlets and in the same vertical plane with the axis of the fan is a projection, 31. The fan 70 chamber, proper, 34, is adapted to be entirely cut off from either of the chambers, 32 and 33, by the valve 35. The valve 35 is shown, in Fig. 2, bridging the points 31 and 36, thereby closing communication between 75 the chambers 32 and 34. When the valve is caused to bridge the points 37 and 31, communication between chambers 33 and 34 is thereby closed. The valve 35 is supported by a part, 38 having arms, 38'—38^a, which 80 have pivotal support around the fan shaft, 28'. An arm, 39, is also pivoted on the shaft 28' and is located without the casing 27. The end 40 is connected, through a slot 41 (Fig. 7) by means of a bolt, 42, with the 85 valve support, 38. The other end, 39^a, of the oscillating arm, 39, is circumferentially slotted as at 43. It has pivotal connection with a current-reversing electric switch, 44, by means of a link, 45. When the arm 39 is 90 moved to dotted-line position the switch is coincidently opened and then closed by such movement, more clearly shown in the schematic view, Fig. 15.

In practically the same exterior casing 95 (see Figs. 3 and 4) air chambers, 46 and 47, are contained. These chambers are surrounded by walls, 48, and are divided by a wall, 49, and a communicating valve, 50. Walls, 51 and 51', with the arched connecting wall, 52, separate the chambers 46 and 47 from the chamber 53. The valve 50 and its housing 52 are preferably truncated cone-shape, the larger end of which communicates with the fan casing 34 at the axis of the fan and the smaller end is opened to the atmosphere and may be closed by the damper, 53'. The valve 50 is shown in position (in Figs. 3 and 9) to close communication between the eye of the fan and chamber 46. When the 105 110

valve is turned to position to bridge the walls 51' and 49 (Fig. 10) communication will be thereby closed between chamber, 47, and the eye of the fan and the opening between chamber 46 and the fan established. 5 The valve may be rotated in the manner described by means of the forked projection 54. When the damper 53' is raised, as shown in Fig. 13, a hose, 55, having a suitable head, 56, may be inserted within the forks of the extension and the hose is thus brought into communication with the eye of the fan. When the valve 50 is turned farther (Fig. 11) until its lower edge is just in touch with 10 the wall 51', both chambers 46 and 47 are shut off from communication with the fan and air may be taken through the hose 55. A removable casing 56 has removable connection with the fan exhaust outlets 29 and 20 30 and may be held in place by means of the screw-threaded ring, 57. The casing, 56, (Fig. 5) is divided into two chambers, 58 and 59, in either or both of which may be contained a heating or cooling medium for 25 heating or cooling the air as may be desired.

In the drawings, I have shown an electric heater, 60, connected to wires $x-y$ by wires 60^a-60^b, and which forms the subject matter for another application filed on even date 30 herewith.

From the fan, air enters the casing, 56, at 61, rises in chamber 58, then passes downwardly through and over the heater 60 in the mixing chamber, 59, and out through the 35 swivel elbow, 62. To give the heated air an upward path the elbow 62 may be turned as shown by dotted lines in Fig. 5. Should the air be cooled by any suitable refrigerating means the heater 60 may be replaced by such 40 a means or device, and the air may be directed downwardly by the elbow 62 when turned as shown in full lines.

In Fig. 12, I have shown a means whereby either of the ends or openings, 32-33, of the 45 fan chamber may be closed, as by means of a screw-threaded disk 63, and a hose 64 thereby connected to any of said screw-threaded openings. An electric motor, 65, is directly connected to the fan shaft, 28', to 50 give rotary movement to said fan, said motor being connected to service mains, A B, through wires x and y and a motor-reversing switch, 44. An air strainer, 66, consisting of a bag of suitable reticulated material may 55 be connected to the elbow, 62, and the latter connected to one of the fan casing or air chamber openings, as shown in Fig. 15, for purposes to be hereinafter described.

The apparatus, as shown, in Fig. 15, may 60 be mounted on a common base 67, and the device may be provided with a vertical end board, 68, and placed within a window and the sash, 69 (Figs. 2 and 3) can be closed down on said board whereby fresh cool air 65 may be taken from the exterior or dust from

the room may be ejected thereinto as occasion may require.

The use and operation of the system are as follows: When the device is to be used for warming the apartment by taking air from the exterior of the room; the valve 35 is turned as shown in Fig. 2; the valve 50 is turned as shown in Fig. 10; at the same time that the valve 35 is moved into this position, by the arm 39, the switch, 44, is thereby closed in such manner as to cause the electric motor to turn the fan anti-clockwise, as viewed in Fig. 2; air, therefore, will be taken into chamber 46, through opening 46^a from the exterior; it will be drawn therefrom through the open port of valve 50 into the eye of the fan, thence projected into the chamber 33 through the opening 30 into chamber 58 (Fig. 5), thence through the heater 60; thence through the chamber 59, 85 and given an upward turn by the elbow 62. When the switch is closed in this manner to cause the motor to turn in the proper direction, the circuit thereby may be coincidentally closed through the electric heater. If it is 90 desirable to simply reheat the air within the apartment, the device may be removed from the window and the air from the apartment will enter the opening 46^a instead of taking cold air from without the apartment, as in 95 the previous example. When it is desirable to reheat the air in the room and to take air also from outside of the room, the device may be placed in the window and the valve 50 may be turned so that the port may be 100 opened into both the chambers, 46 and 47, the openings to the respective chambers being varied in extent to vary the relative proportions of warm and cold air, in a manner clearly apparent.

When it is desirable to use the apparatus for cleaning purposes, the valve 50 may be turned into position, as shown in Fig. 9, and the valve 35 should be turned so as to bridge the gap between 31 and 37, and thereby close communication between the fan chamber proper and the chamber 33, at the same time the reversing switch is operated so as to reverse the direction of the motor to turn the fan clockwise. Air may then be taken from the room through the opening 47^a; through the valve port of valve 50 into the eye of the fan and exhausted outside of the room through opening 29. Instead of exhausting outside of the room the elbow, 62, and bag, 66, may be attached to the screw-threaded end surrounding the opening, 29, and the hose, 64, with nozzle, 55'; and cap 63 may be placed over the opening 47^a and thereby dust may be taken from carpets, rugs, and other furnishings, and exhausted outside of the room or into the dust receiving bag, 66, as desired. The hose and cap may be placed on the end 29 and air may be thereby forcibly projected through the hose to stir up 130

the dust prior to removing the dust as when dust is found in otherwise inaccessible places. All other intakes, may be closed and damper 53 may be opened and the hose 5 and dust nozzle, 53^a, connected thereto, as shown in Figs. 13 and 15, and the dust-laden air taken directly through the cone-shaped hollow valve, 50, and exhausted into the bag, 66, from whence only purified air 10 will escape and wherein the dust will be retained or the dust and air may be exhausted into the outside atmosphere. When it is not desirable to use the casing, 56, containing the heating or cooling medium, it may be 15 readily detached and removed.

While I have herein described my invention in some detail, it will be apparent that many changes might be made from the particular construction and arrangement above 20 described without departure from the spirit of my invention and within the scope of the following claims.

What I claim is:

1. The combination of a fan, a casing providing two exhaust chambers, a valve operable alternately to connect the fan with either chamber to the exclusion of the other, a motor to drive the fan, a reversing switch to control the direction of rotation of the 30 motor, and connections between the switch and valve for automatic movement of the valve in accordance with movements of the switch.

2. In a device of the character described, 35 a fan, a casing providing a fan chamber having tangential outlets and an axial inlet and providing also a co-extensive inlet chamber divided into two compartments, said axial inlet communicating with said 40 compartments, and valves for closure of

either inlet compartment or either outlet to the exclusion of the other.

3. In a device of the character described, a fan, a casing providing a fan chamber having an axial inlet and an inlet chamber co-extensive with the fan chamber and divided into two compartments each communicating with said inlet to the fan chamber, and a conical valve closing communication between the axial inlet and both of said compartments or either thereof to the exclusion of the other, the end of said conical valve having an opening in its end, a closure for said opening, and means to operate said closure, for purposes described. 45 50 55

4. In a device of the character described, a fan, a motor, a shaft connecting said fan and motor, a fan casing for the fan having two outlets, a valve for closing either thereof, and means to operate said valve coincidentally with reversal of rotation of the motor comprising a reversing switch for the motor and an arm, pivoted on said shaft, having connection respectively with said switch and valve for movement of the valve upon movement of the switch from one position to another. 60 65

5. In a device of the character described, a fan inlet chamber having a conical valve seat, a conical valve having an open end, 70 and a projection upon said end of the conical valve to receive a hose, a closure, or for turning said valve, as described.

In testimony whereof I hereunto set my hand in the presence of two witnesses.

FRANK P. MIES.

In the presence of—

W. LINN ALLEN,
MARY F. ALLEN.
